UNITED STATES PATENT OFFICE.

AUGUST A. KLANN, OF WAYNESBORO, VIRGINIA.

ELECTROMAGNETIC RELAY.

Application filed July 24, 1925. Serial No. 45,898.

This invention relates to improvements in electro-magnetic relays, and it consists of the constructions, combinations and arrangements herein described and claimed.

5 An object of the invention is to provide an electro-magnetic relay which is particularly adaptable to uses in pipe organs, one of the improvements residing in the provision of a removable contactor, the removal of 10 which may be effected when required without disturbing any other part of the relay.

Another object of the invention is to provide an electro-magnetic relay in which the stationary contacts are mounted in a novel 15 manner thereby making the work of connecting the necessary wires much easier than at present.

Other objects and advantages will appear in the following specification, reference being had to the accompanying drawing, in which

20 Figure 1 is an elevation of the improved electro-magnetic relay, an associated electrical circuit being illustrated diagrammatically.

Figure 2 is a central vertical section of the relay.

Figure 3 is an inverted plan view of the relay, the guard plate being omitted.

30 Figure 4 is a detail perspective view of the removable contactor.

While the electro-magnetic relay is capable of employment in connection with uses other than the one herein mentioned the 35 particular purpose is to relay electrical current from the contacts 1 and 2 of a key 3 to an electro-magnet 4, which, for example, may be regarded as controlling the air supply to certain organ pipes (not shown).

40 Wires 5 and 6 connect the source of current 7 with one end of the winding of the electro-magnet 8 and with the contact 2 respectively. The wire 9 connects the other end of the magnet winding with the contact

45 1. Upon depression of the key 3 the pull wire 10 draws the contact 2 into engagement with the contact 1, closing the relay circuit and attracting the armature 11. The armature 11 and base 12 are cast of an aluminum alloy. The armature has inserts 13

50 (Fig. 2) of magnetic metal so that the armature is attracted by the electro-magnet. A wire 14 connects one side of the electro-magnet 4 with the source of current 15, a wire

55 16 connecting the other side of the source of current to a screw 17 on the base 12. A wire

18 connects the other side of the electro-magnet with one of a plurality of contacts 19. The remaining fixed contacts will be connected to other and similar magnets (not shown).

A bar 20 rocking in recesses 21 in pendant bosses 22 upon the base 12 furnishes the pivotal mounting of the armature 11. A spring 23, connected at its ends to a projection 24 of the armature and a pin 25 on the base, serves to hold the pivot bar 20 in place but more particularly provides a positive current conductor from the screw 17 to the armature.

70 A contactor 26 is engageable with the fixed contacts 19 when the armature 11 is attracted by the relay magnet 8, as stated. The free extremity of the contactor is slotted at 27 to provide a plurality of contactor 75 fingers equal in number to the fixed contacts. The contactor is bent as shown so that the contacts 19 may be reached. The contactor is easily removable from the armature 11 by loosening the screws 28 and clamp 29. This clamp holds the contactor in place upon the armature, but by loosening the screws, as stated, the contactor is readily removed and replaced by another without disturbing any other parts of the relay. This 80 85 feature is of considerable importance in a device of this kind.

A small piece of felt 30 attached to the free extremity of the armature 11 is contactible with the base 12 when the armature 90 is attracted and serves to deaden any sound. A felt or other washer 31 upon a fixed but adjustable screw 32 limits the downward movement of the armature 11 under the influences of gravity and the spring 23. Jaws 95 33 carry strips of insulation 34 through which the fixed contacts 19 are thrust and by which they are rigidly held. The lower extremities of the strips of insulation are fast upon a short bar of wood 35 to which 100 a guide plate 36 is secured by means of screws or the like.

The operation is doubtless understood already, but may be briefly reviewed to advantage. A depression of the key 3 closes 105 the relay circuit in which the electro-magnet 8 is situated. The energization of this magnet attracts the armature 11 whereupon the fingers of the contactor 26 engage the fixed contacts 19. Each of these contacts 110 may have an entirely independent electrical device, and in the instance of the electro-

magnet 4 the aforesaid engagement of the contacts will cause current to flow from the source 15 over wires 16 and 17, over spring 23 to the armature 11 and to the contactor 26, contact 19, wire 18, electro-magnet 4 and over wire 14 to the other side of the source of current 15.

The particular manner of mounting the contacts 19 makes a more rigid yet simple 10 construction. Again the particular manner of mounting the contactor 26 adds efficiency to the relay. It may happen that one of the contactor fingers breaks. In such event it becomes necessary to remove the entire 15 contactor, and in the improved relay this is done by simply loosening the screws 28 and the clamp 29 so that the contactor is readily taken out and replaced by another.

The electro-magnetic relay takes up but 20 a small amount of space making it possible to assemble a complete set of relays in any easily accessible space which may not be utilized by other parts of the organ in which the relays are used. The base 12 has a right angled portion 37 which is 25 readily applicable to a wood bar 38 for the support of the relays. The relay is further designed to work on a minimum amount of current, taking no more than the ordinary 30 chest magnet. The simplicity of the relay is self-evident because it has only one moving part, namely the armature 11.

I claim:—

1. An organ relay having a plurality of 35 contacts, a movable armature, a contactor which is slotted along one edge to provide a plurality of fingers existing integrally with said contactor which are engageable with the contacts, a clamp plate applicable to the armature and to the contactor along the edge opposite to said fingers, and means including screws by which the clamp plate is tightened upon the contactor to hold it in place.

2. A relay having a plurality of contacts, strips of insulation through which said contacts are thrust for support, a base having jaws between which the strips are clamped, and a non-conducting element including a 50 bar of wood disposed between the strips and assisting in holding them in rigid relationship.

3. A relay having a plurality of contacts, a pair of insulating strips through which the contacts are thrust, a base having two pairs of jaws by which the strips are held in fixed positions, and a spacing element including a bar of wood disposed between portions of the strips.

4. A relay having a plurality of contacts, a pair of insulating strips through which the contacts are thrust, a base having two pairs of jaws by which the strips are held in fixed positions, a spacing element including a bar of wood disposed between por-

tions of the strips, an armature movably mounted upon the base having a contactor engageable with the contacts, and a guard plate supported upon the wood bar extending in the direction of the armature and serving to protect said contactor.

5. A relay comprising a base having bosses provided with recesses, an armature having a bar the ends of which are laid in the recesses thereby providing a fulcrum, a spring attached to the armature at one side of the fulcrum, holding said bar ends in said recesses and tending to move the armature in one direction, and means including an adjustable screw and washer supported by the base and being in position to limit the movement of the armature in said direction.

6. A relay comprising a base having bosses provided with recesses in axial alignment, an armature situated between the bosses having a bar the ends of which are laid in the recesses thereby providing a fulcrum, a spring attached to the armature at one side of the fulcrum holding said bar in said recesses and tending to move the armature in one direction, means including an adjustable screw carried by the base and extending through the armature, said screw carrying a washer in position to limit the movement of the armature in said direction, an electro-magnet mounted upon the base being capable of energization to attract the armature against the tension of said spring, and means including a felt strip embedded in the armature being engageable with the base to limit the movement of the armature by virtue of said attraction and to prevent the making of a sound.

7. A relay comprising a base having recessed bosses on the underside, a right angled portion at the end opposite to said bosses being adaptable to a support for mounting the relay, an electro-magnet mounted upon the base, an armature having a fulcrum bar occupying the recesses and having a projection at one side of the fulcrum, a spring mounted between the base and said projection tending to move the armature in one direction and to limit the movement of the armature in said direction, contacts located beneath said right angled portion, insulating strips by which the contacts are carried, jaws formed beneath said right angled portion by which said strips are clamped in position, means including a wood bar inserted between the strips maintaining them in spaced relationship, a contactor carried by the armature being slotted to provide fingers for engagement with the contacts, and means removably holding the armature in place on the contactor permitting replacement in the event of breakage of one of the fingers.

AUGUST A. KLANN.
